CENTRIFUGAL PUMP

John B. Whitted, Evanston, Ill., assignor to
Stewart-Warner Corporation, Chicago, Ill., a
corporation of Virginia

Application July 27, 1943, Serial No. 496,354

11 Claims. (Cl. 103—87)

1

My invention relates to centrifugal pumps which are particularly adapted for, but not limited to, pumping of fuels for internal combustion engines and similar purposes.

An object of my invention is to provide a new and improved pump which has no shafts or similar moving parts which require packing and which are subject to leakage.

Another object of my invention is to provide a new and improved pump which has no valves which open and close continuously during the operation of the pump and which is substantially noiseless and free from vibration.

Another object of my invention is to provide a new and improved pump which delivers the liquid in a substantially constant stream free from pulsations and other noise and vibration producing characteristics.

Another object of my invention is to provide a simple and inexpensive pump of a new design which will require a minimum of service or other attention.

Another object of my invention is to provide a new and improved centrifugal pump which is highly efficient and which may be located either outside or inside a body of liquid to be pumped.

Other objects and advantages will become apparent as the description proceeds.

In the drawings:

Fig. 1 is a longitudinal, sectional view through a centrifugal pump embodying a preferred form of my invention and showing the operating motor in side elevation;

Fig. 2 is a view of the rotor showing one side broken away;

Fig. 3 is a transverse view taken on the irregular line 3—3 of Fig. 1;

Fig. 4 is an irregular, transverse view taken on the line 4—4 of Fig. 1;

Fig. 5 is a side elevation; and

Fig. 6 is an end view looking in the direction of the arrow 6 of Fig. 5.

The preferred embodiment shown in the drawings comprises a cylindrical member 10 having a cap 12 threadedly secured thereto, as indicated at 14. The member 10 and cap 12 are preferably formed of brass, aluminum, zinc, plastic, or other suitable non-magnetic material and together constitute the pump housing. A fixed diaphragm 50

2

18 of brass or other suitable non-magnetic material is clamped between the member 10 and cap 12 and divides the pump housing into a pumping chamber 18 and a magnet compartment 20. A sealing washer 22 is also clamped between the member 10 and cap 12 and this sealing washer may be made of any suitable non-magnetic material.

In the particular embodiment shown in the drawing, an electric motor, indicated generally by reference numeral 24, is attached to the righthand end of the member 10 by studs 26, or in any other suitable manner. This motor may be of any conventional or suitable type and may be provided with the usual iron or steel housing enclosing the field and armature coils. The motor 24 has a shaft 28 projecting through a suitable opening 30 in the righthand end of member 10 and the projecting portion of this shaft carries a U-shaped, permanent magnet 32 which is held against a shoulder formed in this shaft by a screw 34 and washer 36, the screw being threaded into a tap hold in the end of the shaft. It is to be understood that the magnet 32 is attached to the shaft 28 in such manner that rotation of this shaft rotates the magnet 32.

A rotor is located in the pumping chamber 18 and is driven by rotation of the magnet 32. This rotor comprises an iron or steel bar 38 and non-magnetic discs 40 and 42 of brass or other suitable material secured to the sides of the bar 38 by soldering, welding, or in any other suitable manner. As most clearly shown in Figs. 1 and 2, the bar 38 is elongated and of rectangular cross section, the length of this bar being equal to the diameter of the discs 40 and 42.

The rotor comprising the bar 38 and discs 40 and 42 is mounted on a shaft 44. The righthand end of this shaft rotates in an annular jewel 46 and abuts a second jewel 48. Both of these jewels are carried in a support 50 attached to the fixed diaphragm 18. The support 50 is imperforate, so that no fluid can leak from the pumping chamber into the magnet compartment.

The lefthand end of the shaft 44 is supported in an annular jewel 52 mounted directly in the cap 12. The extreme lefthand end of this shaft is tapered, as indicated at 54, and engages a second jewel 56 carried in a screw 58 adjustably

threaded in a hollow extension 60 of the cap 12. The screw 58 may be adjusted lengthwise of the extension 60 for bearing adjustment and the screw is located in adjusted position by a lock nut 62. A removable cover 64 encloses the head of the screw 58 and lock nut 62 and a sealing gasket 66 is preferably interposed between the cover 64 and cap 12 to form a fluid-tight joint therebetween.

The cap 12 is provided with an inlet passage 68 having a tapped end to receive the threaded end of a fluid supply pipe 70. The passage 68 conducts the fluid to be pumped to the shaft receiving bore 12. It will be noted that the shaft 44 has a central portion of reduced diameter opposite the inlet passage 68 to facilitate flow of fluid from this passage to the shaft receiving bore 12. This particular structure of shaft with reduced central portion and adjacent enlarged portions afford maximum rigidity with minimum size and minimum interference with fluid flow.

The shaft receiving bore 12 has a tapered portion 74 which merges into the pumping chamber 18 to facilitate flow of fluid from the bore 12 into this chamber. Rotor disc 42 has openings 76 opposite the tapered enlargement 74 whereby fluid may flow freely into the fluid chambers 78 and 80 formed on opposite sides of the bar 38 and located between discs 40 and 42.

The magnet 32 has a transverse or base portion 82 and forwardly extending legs 84 and 86. As clearly shown in Fig. 3, the base portion 82 is preferably somewhat wider than the legs 84 and 86 so that the cross sectional area of the magnet is not reduced where this magnet is drilled to receive a motor shaft 28. It will also be apparent that the legs 84 and 86 preferably merge into the base 82 along inner curves to provide maximum flux density at the extreme ends of these legs. These legs attract opposite ends of the bar 38 and this bar normally lies in the plane of these legs but is shown, in Fig. 1, as being at right angles to this plane in order to disclose more clearly the structure of the rotor.

When it is desired to operate my novel pump, the electrical circuit to the motor 24 is closed, whereupon the motor shaft 28 rotates magnet 32. Bar 38 will rotate with the magnet and in the plane of the legs 84 and 86, creating a whirling motion of the liquid in the liquid chambers 78 and 80. The resulting centrifugal force throws this liquid toward the outer circumferential wall of this chamber and the liquid is discharged 35 through outlet passage 88 and discharge pipe 90 attached thereto.

The outward flow of the liquid in chambers 78 and 80 sucks additional liquid through supply pipe 70, inlet passage 68, bore 12, taper 74 and openings 76 into the liquid chambers 78 and 80 to create a continuous flow of liquid between the supply pipe 70 and the discharge pipe 90. There is no mechanical driving connection between the motor and the rotor and fixed diaphragm 16 effectively prevents leakage of liquid from the pumping chamber 18. In normal operation, no leakage would occur around the screw 58, but if such leakage should occur the fluid will merely flow into the cover 64 until this cover is filled with liquid, since gasket 66 effectively prevents leakage between this cover and the cap 12.

The particular pump shown is especially designed to pump gasoline or other liquid fuel into a carburetor having a float valve which completely seals the carburetor inlet when the fuel in the carburetor float bowl is at maximum

height. For such use I have found it desirable to provide my novel pump with a pressure controlled bypass which conducts fluid from the pump outlet to the inlet. This bypass is effective in preventing undue loads on the motor when fuel delivered to the carburetor is prevented by the closing of the float controlled inlet valve. Where the pump is to be used for other purposes, such a pressure controlled bypass may be unnecessary or undesirable and may be omitted.

This pressure controlled bypass comprises a bore 92 connecting outlet passage 88 with a valve chamber 94 having a valve seat 96 and a ball valve 98. A spring 100, confined between the ball 98 and a screw plug 102, urges the ball valve 98 against the seat 96. A bore 104 connects the valve chamber 94 with the pump inlet.

The spring 100 is preselected to permit the bypass valve 98 to open under the desired predetermined pressure. If it is desired to adapt the pump to different conditions, the plug 102 may be unscrewed and another spring of different stiffness substituted to increase or decrease the pressure required to open the bypass valve. A suitable washer 106 is preferably interposed between the plug 102 and a shoulder in the cap 12 to prevent leakage therebetween.

From the foregoing description it will be apparent that I have provided an extremely simple and efficient pump for pumping fuel or other liquids at relatively low pressures. An important feature of my invention resides in the perfect sealing of the pumping mechanism against leakage and the absence of packing glands or other sealing means for preventing leakage about rotating or reciprocating parts. The pump rotor is supported in jewel bearings which require no lubrication and these bearings are capable of affording long and trouble-free service. In the particular embodiments shown the magnet is supported on the motor shaft and this shaft may be mounted in the usual ball bearings which, if properly designed and lubricated, will likewise afford maximum service with a minimum of attention.

It will be noted that my novel pump has no valves which must open and close during the normal operation of the pump. All of the essential elements of the pump are rotating elements which are substantially noiseless so that in the pump shown substantially the only noise will be that created by operation of the motor 24. Such motors can be made to operate extremely quietly so that if desired a substantially silent pump can be provided. If even less noise is desired, a flexible shaft or other driving means could be substituted for the motor 24 and this latter type of driving means is also desirable where it is preferred to submerge the pump in the liquid to be pumped, although sealed electric motors can be used for this purpose if desired.

A further feature of my invention lies in the simplicity and accessibility of the various parts of my novel pump whereby these parts can be readily inspected or replaced if necessary. It should also be noted that a minimum amount of machining is required for the various parts and this machining can be readily performed by conventional machinery, by conventional commercial methods and well within usual tolerance limits.

While I have illustrated and described only a single embodiment of my invention, it is to be understood that my invention may assume nu-

merous forms and that my invention includes all variations, modifications and equivalents falling within the scope of the appended claims.

I claim:

1. A centrifugal pump of the class described, comprising a non-magnetic housing providing a pumping chamber and a magnet compartment, a fixed, non-magnetic diaphragm separating said chamber from said compartment, a power shaft having a free end extending into said compartment and unsupported therein, a magnet located in said compartment and mounted on the free end of said shaft, means for rotating said shaft and said magnet, a magnetic rotor in said pumping chamber driven by said magnet, said rotor including a bar of magnetic material forming the pumping element, an inlet for said pumping chamber, an outlet for said pumping chamber, and means supporting said rotor for rotation with said magnet.

2. A centrifugal pump of the class described, comprising a non-magnetic housing providing a pumping chamber and a magnet compartment, a fixed, non-magnetic diaphragm separating said chamber from said compartment, a magnet located in said compartment, an electric motor for rotating said magnet, a rotor located in said pumping chamber and including an iron bar forming the pumping element, said iron bar being driven by said magnet, an inlet for said pumping chamber, an outlet for said pumping chamber, and a shaft supporting said rotor for rotation with said magnet.

3. A centrifugal pump of the class described, comprising a non-magnetic housing providing a pumping chamber and a magnet compartment, a fixed non-magnetic diaphragm separating said chamber from said compartment, a power shaft having a free end extending into said compartment and unsupported therein, a magnet located in said compartment and mounted on the free end of said shaft, means for rotating said shaft and said magnet, a magnetic rotor in said pumping chamber driven by said magnet, said rotor including a bar forming the pumping element, an inlet for said pumping chamber, an outlet for said pumping chamber, a shaft supporting said rotor for rotation with said magnet, a bearing in said housing for one end of said shaft, and a bearing in said diaphragm for the other end of said shaft.

4. A centrifugal pump of the class described, comprising a non-magnetic housing providing a pumping chamber and a magnet compartment, a fixed, non-magnetic diaphragm separating said chamber from said compartment, a magnet located in said compartment, means for rotating said magnet, a rotor in said pumping chamber driven by said magnet, said rotor comprising a magnetic bar and non-magnetic discs on opposite sides thereof, an inlet for said pumping chamber, an outlet for said pumping chamber and means supporting said rotor for rotation with said magnet.

5. A centrifugal pump of the class described, comprising a housing providing a pumping chamber and a magnet compartment, a fixed diaphragm separating said chamber from said compartment, a magnet located in said compartment, means for rotating said magnet, a rotor in said pumping chamber, driven by said magnet, an inlet for said pumping chamber, an outlet for said pumping chamber, and a shaft supporting said rotor for rotation with said magnet, said shaft

being located in said inlet and having a reduced portion to facilitate flow therethrough.

6. A centrifugal pump of the class described, comprising a non-magnetic housing providing a pumping chamber and a magnet compartment, a fixed, non-magnetic diaphragm separating said chamber from said compartment, a magnet located in said compartment, means for rotating said magnet, a magnetic rotor in said pumping chamber driven by said magnet, said rotor including a bar forming the pumping element, an inlet for said pumping chamber, an outlet for said pumping chamber, means supporting said rotor for rotation with said magnet, a motor for driving said magnet, and means for attaching said motor to said housing in alignment with said rotor supporting means.

7. A centrifugal pump of the class described, comprising a two-part, non-magnetic housing providing a pumping chamber and a magnet compartment, a fixed non-magnetic diaphragm separating said chamber from said compartment and clamped between the parts of said housing, a magnet located in said compartment, an electric motor for rotating said magnet, an iron bar in said pumping chamber driven by said magnet, said bar forming the pumping element, an inlet for said pumping chamber, an outlet for said pumping chamber, and a shaft supporting said bar for rotation with said magnet.

8. A centrifugal pump of the class described, comprising a non-magnetic housing providing a pumping chamber and a magnet compartment, a fixed, non-magnetic diaphragm separating said chamber from said compartment, a magnet located in said compartment, means for rotating said magnet, a rotor in said pumping chamber driven by said magnet, said rotor comprising a magnetic bar, a non-magnetic disc on one side thereof, an inlet for said pumping chamber, an outlet for said pumping chamber, and means supporting said rotor for rotation with said magnet.

9. A centrifugal pump of the class described, comprising a housing providing a cylindrical pumping chamber and a cylindrical magnet compartment, a fixed diaphragm separating said chamber from said compartment, a magnet located in said compartment, means for rotating said magnet, a rotor in said pumping chamber driven by said magnet, an inlet for said pumping chamber, said inlet having a radial portion and an axial portion, an outlet for said pumping chamber, and a shaft supporting said rotor for rotation with said magnet, said shaft being located in said axial portion and having a reduced portion opposite said radial portion.

10. A centrifugal pump of the class described, comprising a housing providing a pumping chamber and a magnet compartment, a fixed diaphragm separating said chamber from said compartment, a U-shaped, permanent magnet located in said compartment, means for rotating said magnet, a magnetic rotor in said pumping chamber driven by said magnet, said rotor comprising a ferrous bar and a disc of non-ferrous material, said bar forming the impeller portion of the said rotor, an inlet for said pumping chamber, an outlet for said pumping chamber, and means supporting said rotor for rotation with said magnet.

11. A centrifugal pump of the class described, comprising a housing providing a pumping chamber and a magnet compartment, non-magnetic means separating said chamber from said compartment, a magnet located in said compartment,

means for rotating said magnet, a magnetic rotor in said pumping chamber driven by said magnet, said rotor comprising a bar of magnetic material and a pair of side members rigid with said bar, one of said side members having a fluid inlet therethrough, an inlet for said pumping chamber, an outlet for said pumping chamber, and means supporting said rotor for rotation with said magnet.
